PAVEMENT MARKER

Application filed July 5, 1928. Serial No. 290,321.

The present invention relates to pavement markers of the kind that are set in the pavement to mark off lines and zones for use in controlling pedestrian and vehicle traffic upon highways and city streets. One object of the invention is to provide a marker which will not materially interfere with the smooth surface of the pavement and yet will possess a maximum of visibility during all conditions 10 of service. Another object is to produce a marker which will adhere to the surface of the pavement with a maximum adhesion in addition to the holding force exerted by the anchorage of the marker to the pavement. 15 Another object is to produce a marker of this class which will have a maximum cushioning action to both the downward and lateral blows of traffic passing over it. Another object is to produce a marker which will be 20 durable and serviceable, economical to manufacture, and easy to install and maintain in efficient condition.

With these objects in view, we preferably construct the marker in the form of a large 25 button having a rubber face. The rubber is in the form of an envelope or covering upon the head of a supporting body or base and the latter includes a stem or shank which depends from the under side of the head and 30 serves as part of a connecting means by which the marker is anchored to the pavement. Ordinarily the stem extends into a hole in the pavement and is screwed home into an anchored nut at the bottom of the hole. The 35 rubber envelope is curved on its upper face and is tapered down at its periphery to a thin edge so as not to present a serious or objectionable obstacle to traffic. The rubber is firmly secured to the base by vulcanization 40 or other suitable process or means. The thin peripheral lip also closely fits irregularities in the surface of the pavement. The same close adhesion of the rubber rim to the pavement furnishes a water seal and thus prolongs 45 the life of the marker by preventing the seepage of water to its under surface. By using cement, the adhesion of the marker to the pavement may be greatly increased. Likewise, concentric ribs on the under side of the 50 rubber envelope engage the pavement and

increase the cushioning action and hence the suction between the two and consequently increase the adhesion of the marker to the pavement. The suction action over the greater portion of the under surface may be slight, 55 but it will occur whenever a downward movement of the head is followed by an upward movement, provided of course there is a good seal between the pavement and the edge of the rubber envelope. Such suction producing 60 movements of the whole head may occur at times by reason of the heavy blows of traffic and at other times they may result from expansion of the metal parts of the marker under temperature variations. But in addition to this general movement of the body, as 65 a whole, it is clear that almost every blow of traffic will press the periphery of the rubber envelope down and this will be followed, when time between blows will permit it, by 70 a tendency of the rubber to return to its initial position. Such return, whether partial or complete, will produce suction action at the periphery, provided of course as before that there is a good seal at the peripheral 75 edge of the marker. The rubber is given a chrome orange color which renders the marker most easily discernible under the variable conditions of weather and service. By using this color we believe we have a maximum visibility at all times. The rubber has high wearing properties and hence its use increases the life of our marker over mere metal markers such as have been proposed heretofore. 80

With these general observations, we may 85 pass to a consideration of a fuller disclosure of the invention set forth in the following detailed description and accompanying drawings. The scope of the invention will be particularly pointed out in the appended 90 claims.

In said drawings, Fig. 1 is a vertical section of a marker constructed in accordance with the present invention and shown loosely seated in the pavement; Fig. 2 is a top plan view of the marker; Fig. 3 is a bottom plan view of the same; and Fig. 4 is a view similar to Fig. 1 showing the marker screwed home and thus firmly seated in and upon the pavement, Figs. 2 and 3 being on a reduced 100

scale. These figures illustrate the preferred embodiment of the invention. Throughout these views like characters refer to like parts.

Referring to the drawings in detail, A designates the main supporting member or base of the marker. This member comprises a disk-like head 21 and a stem or shank 22. In the present instance, the head 21 and the stem 22 are integral and constitute a single metal casting, cast iron or cast steel being preferably employed. The head 21 is circular in outline and preferably slightly conical, the sides of the cone extending from the apex 22 to points 23 adjacent to the periphery. Obviously, the outline of the head may take other forms than the circle but in any event the form is preferably that of a plane figure. The portion of the upper surface outward of the points 23 curves down to meet the under surface of the head and thus form a finished edge. The portion of the head which extends beyond the stem or hub 22 constitutes in reality a flange 24. This flange is adapted to overlie the pavement 25 while the stem 22 is adapted to enter a hole or opening 26 in the pavement.

Preferably the entire upper face of the head 21 and the under side of the flange 24 are inclosed in an envelope B of rubber. The upper surface of the rubber is curved and has a substantial thickness so as to provide a good wearing face capable of use for a long period of years. In this connection it may be pointed out that a rubber facing such as we employ will stand up well as a paving surface. This has been established by certain experiences with rubber surfaced pavements in England. The resiliency of this envelope takes up the shock of the traffic over it and transmits but little shock to the supporting member and anchorage and thus the marker remains tight in the pavement a great length of time as well as being long lived in wearing qualities.

The envelope B does not require the same thickness on the under side of the flange 24 as it does on the upper or wearing side. But the portion on the under side preferably has thereon a plurality of concentric ribs 28 formed concentrically with the hub 22. The periphery of the envelope B also curves downward to provide a downwardly and outwardly extending lip 29. This lip extends all the way around the marker and is relatively thin and flexible and consequently conforms itself readily to irregularities in the surface of the pavement 25. In forming this lip we preferably curve the under side of the lip 29 outward and downward the same as the upper side of the lip. This gives the lip a downwardly inclined position when it is free, and the marker is not in final position upon the pavement. When the latter position is reached then the lip flattens

out more or less, in the manner illustrated in Fig. 4.

At the time the marker is being screwed home into its final position, the ribs 28 and the lip 29 first engage the pavement surface and then upon further screwing will drive out more or less of the entrapped air just as a suction cup will drive out air when pressed against a smooth surface. This, of itself, produces no suction, but any subsequent movement of the marker head or portions of it away from the pavement will produce suction. Such upward movement of the head, as a whole, may occur by rebound of the marker head after a heavy depressing blow from heavy traffic. Expansion of the parts, as in summer, may also produce it. The tendency, however slight, produces an action which tends to hold the marker in place rather than to loosen it. Besides this, there is the up and down movement of the outer edge of the envelope of rubber. The peripheral portion of this envelope beyond the metal head 21, terminating in the lip 29, is free to rise and fall under the blows of traffic. Practically every such blow will depress this free peripheral portion of the rubber at one point or another, and in response to each blow the rubber returns wholly or partially to its normal position and the repeated blows and returns bring about some suction. The compressing movement drives out more or less of the entrapped air which is present in the space above the pavement between the outermost rib 28 and the lip 29, and the return movement of this portion of the envelope produces suction at the periphery. Of course all this action is dependent upon there being a close fit between the lip 29 and the pavement. But the lip is tapered down and outward just for this purpose. It normally reaches to or a little beyond the plane of the lower ends of the ribs 28 to insure this result. This suction, whether of the head as a whole or of just the periphery of the envelope, is, even though slight, a force acting in the right direction. It is a force which tends to hold the marker to the pavement, rather than to eject it from it. And the peripheral suction also serves to keep the peripheral edge of the rubber envelope from turning up under the strains and blows of service.

The envelope B also preferably incloses a portion of the stem 22 as indicated at the point 30. Obviously in practice the extent of the envelope on the under side of the head 21 and along the stem 22 may be varied without departing from the scope of our invention. Where the same extends over the bottom of the flange 24 and then down over a portion of the shank 22 it cooperates with the more or less irregular edge of the pavement surrounding the hole 26 to form a second water seal between the pavement and the

marker. The rubber at this point also provides a cushion between the head A and the pavement 25. Of course the effectiveness of the seal and cushion thus produced about the 5 hole 26 depends upon the care with which the hole 26 is cut in the concrete or other material of the pavement. The fit must be close enough to permit the rubber to firmly engage the paving material about the hole, 10 otherwise no seal or cushion will result. Obviously, the marker may be used either with or without this care and the resulting advantages.

The rubber envelope B is made to adhere 15 firmly to the supporting member A by first sand-blasting the member and then preferably also copper-coating the same. When this is done then the rubber is filled into molds about the head A and subsequently pressure and heat are applied to firmly force the rubber into contact with the member A and to vulcanize the rubber. The rubber is a high grade resilient product and is preferably orange in color. The latter is produced by 20 introducing a chrome pigment obtained from lead chromate. Obviously, the rubber may vary in composition but it is desirable to have a high grade rubber which will withstand traffic wear for a number of years. This 25 enables the envelope to be thin enough on the upper face of the base member A to produce a minimum of difference in elevation between the top of the marker and the pavement. Having the rubber of a high grade 30 and resilient quality also enables the peripheral lip 29 to readily conform to slight irregularities in the pavement, and the thin edge which constitutes this lip will not then readily wear out, but will last for a long 35 time. The color of the envelope, of course, might be varied, but we believe that the chrome orange has been found by test to be the one possessing the greatest visibility in all conditions of weather. This color, too, 40 should show up clearly on the pavement when the latter is wet and the marker is more or less obscured by the dirt of the road.

The anchorage may vary considerably in 50 practice. A simple form of anchoring device is illustrated. This includes an anchor bolt 31 screwed into a threaded hole tapped into the under side of the stem 22. The lower end of the bolt 31 is threaded into a nut 32. The latter is positioned at the bottom of a 55 hole 33 in the pavement and is held therein by a packing 34. The hole 33 is somewhat smaller in diameter than the hole 26, but it is large enough to readily take in the nut 32 and allow the same to be packed in place by the 60 packing 34. This placing of the nut 32 may be done before the bolt 31 is screwed into it. The packing 34 is ordinarily lead and the irregular outer surface of the nut 32 prevents its withdrawal when once the packing 65 is completely in place. Ordinarily, in as-

sembling the parts, the nut is first positioned at the bottom of the hole 33 and securely packed, then the marker with the anchor bolt 31 in place in the stem 22 is screwed into the nut 34. The parts are at first brought 70 into the position illustrated in Fig. 1, and then as the marker is screwed home the parts are moved to the position shown in Fig. 4. The early part of the screwing operation 75 may be performed by hand, but later on it may be necessary to employ a special tool for holding the marker and turning it to complete the setting of the same in the pavement. A tool having a suction head to fit the upper 80 face of the marker has been proposed for this purpose.

In carrying out the invention it is clear 85 that different types of heads and stems may be employed without departing from the spirit and scope of the invention. In some instances, too, the rubber envelopes may not completely cover the upper faces of the heads because of the ways employed in securing the heads to the pavement. Hence, in the claims 90 we have included the word "substantially" 95 when defining this feature in order to cover obvious modifications of the preferred structure. Still other changes will occur to workers in this art.

In view of these facts, we do not wish to 100 be limited to the exact details illustrated and described but aim to cover all alterations and modifications which rightly come within the scope of our invention, by the terms of the appended claims.

What we claim as new and desire to secure by Letters Patent of the United States is:

1. A pavement marker of the class described comprising a head, a stem extending downward from said head, and an envelope 105 of rubber covering substantially the entire top of said head and extending outwardly over its periphery and back over its under surface toward said stem, the under face of that portion of the envelope which lies directly beneath said head being provided with elevations and depressions constituting cushioning means.

2. A pavement marker of the class described comprising a head, a stem extending downward from said head, and an envelope 115 of rubber covering substantially the entire top of said head and extending outward over its periphery and back over its under surface toward said stem, the under face of that portion of the envelope which lies directly beneath said head being provided with elevations and depressions constituting cushioning means, and the peripheral portion of said envelope out beyond said cushioning means 120 forming a thin peripheral lip normally extending outward and downward and operative to closely fit irregularities in the pavement and to make a good seal with the same.

3. A pavement marker of the class de-

scribed comprising a head, a stem extending downward from said head, and an envelope of rubber covering substantially the entire top of said head and extending outward over its periphery and back over its under surface towards said stem, the under surface of that portion of the envelope which lies directly beneath said head being formed with a plurality of upstanding ribs concentric with said stem, said ribs and the depressions between them constituting cushioning means.

4. A pavement marker of the class described comprising a head, a stem extending downward from said head, and an envelope of rubber covering substantially the entire top of said head and extending outward over its periphery and back over its under surface towards said stem, the under surface of the portion of the envelope which lies directly beneath said head being formed with a plurality of upstanding ribs concentric with said stem, said ribs and the depressions between them constituting cushioning means, and the peripheral edge of said envelope out beyond said ribs being a thin lip normally extending outward and downward and operative to fit irregularities in the pavement and to make a good seal with the same.

5. A pavement marker of the class described comprising a head, a stem extending downward from said head, an envelope of rubber covering substantially the entire top of said head and extending outward over its periphery to form a peripheral lip and back over a portion of its under side to form a cushion underneath a portion of the under side of said envelope adjacent to the periphery of said head having a pavement-engaging upstanding rib concentric with said stem, said peripheral lip being thin at its outer edge and normally extending outward and downward and operating to fit irregularities in the pavement and to make a good seal with the same, said rib and lip normally terminating in substantially the same plane, said plane being perpendicular to the axis of said stem.

6. A pavement marker of the class described comprising a head, a stem extending downward from said head, and an envelope of rubber covering substantially the entire top of said head and extending outward beyond its periphery to form a peripheral lip and back over a portion of its under surface to form a cushion underneath, a portion of the envelope beneath said head being provided with an annular pavement-engaging elevation and outward therefrom with an annular depression, said depression being just inward of said lip, said peripheral lip being thin at its outer edge and normally extending outward and downward from the periphery of said head and operating to closely fit irregularities in the pavement and to make a good seal with the same.

7. A pavement marker of the class described comprising a head, a stem extending downward from said head, and an envelope of rubber covering substantially the entire top of said head and extending outward beyond its periphery to form a peripheral lip and back far enough to underlie the peripheral edge of said head, the portion underlying said peripheral edge having an upstanding pavement-engaging rib concentric with said stem, said peripheral lip being thin at its outer edge and normally extending outward and downward and operating to fit irregularities in the pavement and to make a good seal with the same, said rib and lip normally terminating in substantially the same plane, said plane being perpendicular to the axis of said stem.

8. A pavement marker of the class described comprising a head, a stem extending downward from said head, and an envelope of rubber covering substantially the entire top of said head and extending outward beyond its periphery to form a peripheral lip and back far enough to engage the under side of the peripheral edge of said head, the portion thus engaging said under side forming an annular elevation separated from said lip by a depression, said peripheral lip being thin at its outer edge and normally extending outward and downward from the periphery of said head and operating to closely fit irregularities in the pavement and to make a good seal with the same.

9. A pavement marker of the class described comprising a relatively flat head, a downwardly extending stem secured at its upper end to said head against relative up and down movement, and a single envelope of rubber of the same quality throughout substantially enclosing said head and having an outwardly extending pavement-engaging peripheral lip extending entirely beyond the periphery of said head and a pavement-engaging rib separated from said lip by a depression, said rib, lip and depression co-operating with the surface of the pavement to establish good contact between said lip and pavement.

In testimony whereof we hereunto subscribe our names this 2nd day of July, 1928.
